UNITED STATES PATENT OFFICE

98,360

DESIGN FOR A BOUDOIR CASE

Max C. Meyer, Brooklyn, N. Y.

Application July 17, 1935, Serial No. 57,683

Term of patent 3½ years

To all whom it may concern:

Be it known that I, Max C. Meyer, a citizen of the United States and a resident of No. 250 Underhill Avenue, in the Borough of Brooklyn, city and State of New York, have invented a new, original, and ornamental Design for a Boudoir Case, of which the following is a specification, reference being had to the accompanying drawing, forming part thereof, of which the following is a description:—

The figure represents a perspective view of a substantially cylindrical boudoir case having a base fixed to the body thereof and a removable head upon which rests a floral representation, the base and head both being of greater diameter than the body, and the body having a circular ribbed or beaded conformation. The rear of the element is identical with that portion shown in the drawing.

I claim:

The ornamental design for a boudoir case, as shown and described.

MAX C. MEYER.
